(57) **CLAIM**

The ornamental design for a "cover for a seating device," as shown and described.

DESCRIPTION

FIG. 1 is a perspective view showing our seat cover;
FIG. 2 is a front view of FIG. 1;
FIG. 3 is a rear view of FIG. 1;
FIG. 4 is a right side view of FIG. 1;
FIG. 5 is a left side view of FIG. 1;
FIG. 6 is a bottom side view of FIG. 1;
FIG. 7 is a top side view of FIGS. 1; and,
FIG. 8 is a perspective view showing our seat cover.
All dotted lines in the drawings depict probable environment only and form no part of the claimed design.
